UNITED STATES PATENT OFFICE

157,033

DISPLAY RACK

Homer C. Douglas, Kansas City, Kans.

Application March 29, 1948, Serial No. 145,415

Term of patent 3½ years

(Cl. D80—9)

To all whom it may concern:

Be it known that I, Homer C. Douglas, a citizen of the United States, residing at Kansas City, in the county of Wyandotte and State of Kansas, have invented a new, original, and ornamental Design for a Display Rack, of which the following is a specification, reference being had to the accompanying drawing, forming a part thereof.

Fig. 1 is a side elevational view of a display rack, showing my new design.

Fig. 2 is a front elevational view thereof; and, Fig. 3 is a top plan view thereof.

The back of the rack is substantially plain.

I claim:

The ornamental design for a display rack, as shown and described.

HOMER C. DOUGLAS.
